GEORGE L. CORCORAN AND GEORGE A. DOBYNE, OF ST. LOUIS, MISSOURI, ASSIGNORS, BY DIRECT AND MESNE ASSIGNMENTS, TO CHAMPION SHOE MACHINERY COMPANY, OF ST. LOUIS, MISSOURI, A CORPORATION OF MISSOURI.

PRESSER-BAR-ACTUATING MECHANISM.

SPECIFICATION forming part of Letters Patent No. 751,263, dated February 2, 1904.

Application filed February 20, 1903. Serial No. 144,319. (No model.)

To all whom it may concern:

Be it known that we, GEORGE L. CORCORAN and GEORGE A. DOBYNE, citizens of the United States, residing at St. Louis, Missouri, have 5 jointly invented a certain new and useful Improvement in Presser-Bar-Actuating Mechanism, of which the following is a full, clear, and exact description, such as will enable others skilled in the art to which it appertains to 10 make and use the same, reference being had to the accompanying drawings, forming part of this specification, in which—

Figure 1 is a side elevation. Fig. 2 is a top plan view on about the line 2 2 of Fig. 1, the 15 presser-bar being shown in section. Fig. 3 is an elevation, partly in section; and Fig. 4 is an elevation, partly in section, looking from the left of Fig. 1.

Our invention relates to improvements in 20 mechanism for actuating presser-bars, being particularly applicable in connection with sewing-machines, although in no wise limited to such use.

Our object is to provide means whereby the 25 presser-bar can be clamped and elevated and then released in order to permit the presser-foot to return to its position upon the work.

To this end and also to improve generally upon mechanism of the character indicated 30 our invention consists in the various matters hereinafter described and claimed.

In the accompanying drawings we have shown the invention as applied in connection with a sewing-machine, only so much of the 35 sewing-machine being illustrated as is necessary to enable the present invention to be thoroughly understood.

In said drawings, A indicates the supporting-standard of the machine, and 3 is a head 40 upon said standard, by which head the presser-bar 10 is supported and in which the same is guided in its reciprocations, and spring 11 coiled about said presser-bar and lying between some suitable portion of the machine-head and 45 a collar 12 upon said bar serving to yieldingly hold the bar with its presser-foot in work-en-

gaging position and also serving to return the presser-bar to its position with its foot in engagement with the work after said bar has been elevated and released. The presser-foot E is 50 secured to the bar in any suitable manner.

C represents the work-table, between which and the presser-foot the work is clamped in a well-understood manner, and W indicates the work.

A rock-shaft 30, suitably supported on the machine-standard, receives power from any suitable source and has connected thereto a rock-arm 31.

About the presser-bar is a yoke or bail 33, 60 between whose arms is pivoted a lifting-bar 34, whose inner end is provided with a cam or eccentric surface 35. Between the presser-bar and the inner end of said lifting-bar and upon the side of the presser-bar opposite to that engaged by the said yoke is a block 36, whose lifting-bar-engaging surface 37 preferably conforms to the said cam-surface 35. The upper portion of said block is preferably provided with overhanging edges 38, which rest upon the 70 arms of the bail and also upon the lifting-bar, whereby said block is supported, and extending from the lower portion of said block and upon the side of the pivotal center of the lifting-bar opposite that upon which the inner end of 75 said bar lies is a stop or rest 39, the lifting-bar when in its releasing position coming to rest between the said stop 39 and the overhanging lip 38, whereby the downward movement of the free end of the lifting-bar about 80 its pivot is limited. The bail 33 normally rests upon some suitable portion, as 40, of the head 3.

Depending from the rock-arm 31 is an arm 41, which carries a projection 42, (preferably 85 a roller,) lying under and adapted at certain times to engage the under surface of the outer portion of said lifting-bar 34, while also depending from the rock-arm 31 is a pivoted arm 43, which has a lower angular extension 90 44, provided with a member, preferably an adjustable set pin or screw 45, lying below

and in line with the block 36. The arm 43 is preferably held in its desired position, engaging the presser-bar in order to be guided thereby, by a spring 46, connected to said arm and to the rock-arm 31. As the rock-arm rises the roller 42 engages the lifting-bar 34, and as it rocks said lifting-bar about its pivot the presser-bar is clamped between the bail and the block 36, whereby in the further upward rocking of said rock-arm 31 the presser-bar is lifted in a manner which will be apparent. The releasing-arm 43 is farther from the center of oscillation of the rock-arm 31 than is the locking-arm 41, whereby for the same amount of movement of the rock-arm 31 the releasing-arm 43 travels a greater distance than does the locking-arm 41. Thus at the desired point in the upward movement of the rock-arm 31 the screw or pin 45 engages the block 36, (preferably upon an inclined surface 47,) and thus lifts the said block and releases the presser-bar, whereupon the spring 11 forces the presser-bar downwardly.

By reason of the construction above described when the parts are in normal position, as shown in Fig. 1, the presser-foot bears upon the work and is held against the same by the spring 11, the presser-bar being, however, not engaged by the clamp, so that said bar is free to yield, and thus accommodate itself to inequalities in the thickness of the work. The lifting-bar 34 is so held by the block 36 that the outer end of said bar cannot fall, and thus tend to wedge the block 36 against the presser-bar when the parts are in normal position. When, however, it is desired to lift the presser-bar, said bar is firmly clamped and elevated.

The releasing mechanism is extremely simple and is positive in its operation, it being possible to adjust the releasing-screw 45, and thus vary the time at which the presser-bar is released in order to suit the convenience of the operator. The releasing-arm is properly guided by the presser-bar itself, thus avoiding the use of additional parts, and said releasing-arm can swing about its pivot in order to prevent binding of the parts. Furthermore, as the screw 45 engages a surface of the block 36, which is inclined away from the engaging end of the screw and toward the presser-bar, the said screw when releasing the clamp tends to move the block 36 away from the presser-bar, and thus prevents said block from binding upon the presser-bar as said bar descends.

We are aware that minor changes in the construction, arrangement, and combination of the several parts of our device can be made and substituted for those herein shown and described without in the least departing from the nature and principle of our invention.

Having thus described our invention, what we claim as new, and desire to secure by Letters Patent, is—

65 1. In a sewing-machine, the combination with

a presser-bar and its work-engaging presser-foot, of a clamp coöperating with said presser-bar, clamp-actuating means for throwing said clamp into clamping position and moving the same to elevate said presser-foot, and releasing mechanism supplementary to said clamp-actuating means for automatically throwing said clamp into releasing position while said clamp-actuating means is in position to hold said clamp in clamping position; substantially as described.

2. In a sewing-machine, the combination with a presser-bar and its work-engaging presser-foot, of a clamp coöperating with said presser-bar and including a movable clamping member, clamp-actuating means for throwing said clamp into clamping position and moving the same to elevate said presser-foot, and a releasing part supplementary to said clamp-actuating means and adapted to engage said clamp member during its said movement and thus throw the same from clamping position; substantially as described.

3. The combination with a presser-bar, of clamping members coöperating with the same, a movable element, means whereby, in the movement of said element, said clamping members are caused to clamp said presser-bar, and a releasing part supplementary to said means, said releasing part being supported directly upon and carried by said movable element and adapted in the movement of the same to engage one of said clamping members and move the latter out of clamping position; substantially as described.

4. The combination with a presser-bar, of clamping members coöperating therewith, a clamp-actuating part connected to said clamping members, a rock-arm adapted in its movement to engage and move said clamp-actuating part, whereby, in the movement of said rock-arm, said clamping members are actuated to clamp said presser-bar, and a releasing part supplementary to said clamp-actuating part, said releasing part being supported directly upon and carried by said rock-arm and adapted to engage one of said clamping members to cause the latter to release said presser-bar; substantially as described.

5. The combination with a presser-bar, of clamping members coöperating therewith, a clamp-actuating part connected to said clamping members, a rock-arm adapted in its movement to engage and move said clamp-actuating part, whereby, in the movement of said rock-arm, said clamping members are actuated to clamp said presser-bar, and a releasing part supplementary to said clamp-actuating part, said releasing part being supported directly upon and carried by said rock-arm and adapted to engage one of said clamping members to cause the latter to release said presser-bar, said rock-arm having engagement with said clamp-actuating part at a point intermediate said releasing part and the axis of

oscillation of said rock-arm; substantially as described.

6. The combination with a presser-bar, of clamping members coöperating therewith, a clamp-actuating part connected to said clamping members, a rock-arm adapted in its movement to engage and move said clamp-actuating part, whereby, in the movement of said rock-arm, said clamping members are actuated to clamp said presser-bar, and a releasing-arm supplementary to said clamp-actuating part and pivotally supported directly upon said rock-arm; substantially as described.

7. The combination with a presser-bar, of clamping members coöperating therewith, a rock-arm having engagement with a part connected to said clamping members for causing them to engage said bar, and a releasing-arm pivotally supported upon said rock-arm and having its free end in engagement with said presser-bar; substantially as described.

8. The combination with a presser-bar, of a bail about said bar, a lifting-bar pivotally supported upon said bail, a clamping-block intermediate the inner end of said lifting-bar and said presser-bar, a rock-arm, a releasing device supported directly upon said rock-arm, and a part upon said rock-arm intermediate its axis of oscillation and said releasing device and adapted to engage said lifting-bar; substantially as described.

9. The combination with a presser-bar, of a bail about said bar, a lifting-bar pivotally supported upon said bail, a clamping-block intermediate the inner end of said lifting-bar and said presser-bar, a rock-arm, a releasing-arm pivotally supported directly upon said rock-arm, and a part upon said rock-arm intermediate its axis of oscillation and said releasing-

arm and adapted to engage said lifting-bar; substantially as described.

10. The combination with a presser-bar, of clamping members coöperating therewith, a rock-arm having engagement with a part connected to said clamping members for causing them to engage said presser-bar, a releasing-arm pivotally supported upon said rock-arm and engaging a guide-surface, and means for holding said releasing-arm under tension against its said guide-surface; substantially as described.

11. The combination with a presser-bar, of clamping members coöperating therewith, a rock-arm having engagement with a part connected to said clamping members for causing them to engage said bar, a releasing-arm pivotally supported upon said rock-arm and having its free end guided by said presser-bar, and a spring connected to said releasing-arm and said rock-arm for holding said releasing-arm against said presser-bar; substantially as described.

12. The combination with a presser-bar, of clamping members coöperating therewith, means for operating said clamping members, and a releasing member adapted to enter between said bar and a portion of one of said clamping members and to engage the latter, the engaging surface of one of said parts being inclined; substantially as described.

In testimony whereof we hereunto affix our signatures, in the presence of two witnesses, this 30th day of January, 1903.
